[57] CLAIM

The ornamental design for a cassette tape magazine, as shown and described.

DESCRIPTION

FIG. 1 is a front, bottom and side isometric view of a cassette tape magazine showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right end elevational view thereof;

FIG. 7 is a left end elevational view thereof; and

FIG. 8 is a front, bottom and side isometric view thereof.

The broken line showing of reels and tape in FIG. 8 is for illustrative purposes only and forms no part of the claimed design.

FIG. 1

FIG. 8
